(US)

(57) **CLAIM**
The ornamental design for a front bezel for disk drive storage enclosure, as shown and described.

(73) Assignee: **nStor Technologies, Inc.**

DESCRIPTION

(**) Term: **14 Years**

FIG. 1 is an upper front perspective view of the front bezel for a disk drive storage enclosure in accordance with the invention;

(21) Appl. No.: **29/133,559**

FIG. 2 is a lower front perspective view thereof;

(22) Filed: **Dec. 1, 2000**

FIG. 3 is a lower rear perspective view thereof;

(51) LOC (7) Cl. **14-02**

FIG. 4 an upper rear perspective view thereof;

(52) U.S. Cl. **D14/445**

FIG. 5 is a first side view thereof;

(58) Field of Search D14/441-446;
D13/162, 184, 199, 164, 177; 312/223.2;
361/680-686

FIG. 6 is a top plan view thereof;

(56) **References Cited**

FIG. 7 is a second side view thereof;

U.S. PATENT DOCUMENTS

FIG. 8 is a bottom plan view thereof;

D. 349,494 * 8/1994 Aderman et al. D14/445
D. 380,211 * 6/1997 Aderman et al. D14/445
D. 415,749 * 10/1999 Burke D14/445

FIG. 9 is an enlarged first end view thereof; and,
FIG. 10 is a second end view thereof.

The broken lines shown throughout the drawing figures are included for the purpose of illustrating the structure of the front bezel only and form no part of the claimed design.
